UNITED STATES PATENT OFFICE.

WILLIAM A. COST, OF INDIANAPOLIS, INDIANA, ASSIGNOR TO J. D. ADAMS & COMPANY, A COPARTNERSHIP CONSISTING OF R. E. ADAMS, W. R. ADAMS, LEONA H. ADAMS, HELEN J. ADAMS; R. E. ADAMS, W. R. ADAMS, AND S. E. HENRY, TRUSTEES; AND R. E. ADAMS AND W. R. ADAMS, EXECUTORS OF THE ESTATE OF J. D. ADAMS, DECEASED.

ROAD GRADER.

Application filed August 9, 1924. Serial No. 731,022.

To all whom it may concern:

Be it known that I, WILLIAM A. Cost, a citizen of the United States, residing at Indianapolis, in the county of Marion and State of Indiana, have invented a new and useful Road Grader, of which the following is a specification.

It is the object of my invention to produce a spring counterbalance for the blade and blade-carrying parts of a road-grader, which counterbalance will be effective throughout a greater range of vertical movement of the grader blade than previous counterbalances have been. A further object of my invention is the support of the grader blade by means of the spring counterbalance so that chattering is avoided when taking light cuts with the blade, such as in road maintenance work.

I accomplish the above objects by providing a road grader with two springs which act between the grader frame and the blade-carrying member, and I provide one of such parts with means for equalizing the tension of said two springs, such tension-equalizing means being herein described as a pivoted bar to the ends of which the springs are attached.

The accompanying drawing illustrates embodiments of my invention in which the pivoted bar is mounted on the grader frame:— Fig. 1 is a perspective view showing my invention as applied to a road grader; Fig. 2 is a detail view showing the method of attaching the spring to the lift angles of the grader draw-bar; Fig. 3 is a plan view of a modification of my invention in which the lower ends of the springs are directly attached to the grader mold-board; and Fig. 4 is a transverse section of a grader embodying the arrangement shown in Fig. 3.

My invention may be applied to any road grader having a frame and a vertically adjustable blade. The road grader shown has a wheel-supported main frame 10, a draw-bar 11, a pivoted semi-circle 12 mounted on the under side of said draw-bar, and a mold-board 13 supported by said semi-circle. The draw-bar 11 is provided with transverse members or lift-angles 14, the ends of which are connected by lift links 15 to the eccentric ends of rotatable lift-arms 16. The lift

arms 16 may be rotated through suitable gearing by the hand wheels 17.

Pivotedly supported above the frame 10 by means of the legs 20 and bolt 21 is a transversely extending bar 22. Connected to each end of the bar 22 is a coil spring 23 which extends downwardly from such bar 22 and at its lower end is connected to some convenient point on the draw-bar such as to the lift angles 14. The means by which the springs 23 are attached to the draw-bar and the exact location of such attachment is not a part of my invention, but by way of example I have shown the lower end of each spring 23 as being formed into an eye which engages a hook 24 bolted against the lower side of the draw-bar lift angles 14 near each end thereof.

In the modification of my invention illustrated in Figs. 3 and 4, I attached the upper ends of the springs 23 to a pivoted bar 25, similar to the pivoted bar 22 of Fig. 1, and I attach the lower ends of the springs 23 directly to the mold-board 13 instead of to the draw-bar lift angles 14. As the mold-board is angularly adjustable about a vertical axis, I prefer to mount the bar 25 so that it may swing about substantially the same vertical axis when the angular adjustment of the mold-board is changed. To accomplish this, I provide a bearing 26 in which is pivotally mounted a yoke 27 in such a position that its axis of pivotal mounting substantially coincides with the axis about which the mold-board 13 is adjustable. The bar 25 is pivotally mounted in the yoke 27 by means of the pin 28 which passes through the yoke and the bar.

The springs 23 are made of such proportions that they substantially counterbalance the weight of the mold board, semi-circle, draw-bar, and attached parts, when the lower edge of the mold board is a slight distance above the ground. If the mold-board is lowered from this position at which the weight of the movable parts is counterbalanced by the springs, the lifting force exerted by the springs is greater than the weight of the movable parts. As a result of this, all lost motion existing between the hand wheel 17 and mold-board 13 is taken up by the springs whenever the blade is

below that position in which the springs exactly counterbalance the weight of the mold-board and its supporting parts. If the grader is being used in maintenance work 5 or is taking a light cut, the blade will not chatter or drop down into soft or low places in the road, as it is securely held in definite position by means of the counterbalance springs 23 acting in opposition to the lifting mechanism.

The force exerted by either spring 23 varies with the length of this spring. The longer the spring in comparison to the distance through which it is stretched the 15 smaller will be the proportionate variation in the force exerted by the spring as it is stretched. As it is desirable to keep the variation of the force exerted by the spring within as small a range as possible, long 20 springs are desirable. Aside from the equalizing of the tensions of the two springs, my invention has an added advantage in that 25 it has the effect of doubling the length of the spring; for if either hand wheel is rotated to raise or lower one side of the draw bar, the resultant spring displacement is divided between the two springs, and thus 30 the ratio of spring length to extension is increased and the variation in the force which the springs exert is lessened.

I claim as my invention:

1. In a road grader having a frame and a vertically movable element which includes a mold-board; the combination of a transverse bar pivotally mounted on said frame and two springs acting between said movable element and said bar, said springs being attached to said bar on opposite sides of its axis of pivotal mounting.
2. In a road grader having a frame and a vertically movable element which includes a mold-board; the combination of a transverse bar pivotally mounted on said frame and a spring acting between each end of 45 said bar and said movable element.
3. In a road grader having a frame and an element vertically movable beneath said frame; the combination of a transverse bar pivotally mounted above said frame and 50 two tension springs acting between said

movable element and said bar, said springs being attached to said bar on opposite sides of its axis of pivotal mounting.

4. In a road grader having a frame and a vertically movable element which includes 55 a mold-board; the combination of two springs acting between said frame and said movable element and tending to counterbalance the weight of said movable element, and means for equalizing the stress on said two springs.

5. In a road grader having a frame and a vertically movable element which includes a mold-board; the combination of two tension springs acting between said frame and 65 said movable element and tending to counterbalance the weight of said movable element, and means for equalizing the tension of said two springs.

6. In a road grader having a main frame, 70 wheels for supporting said main frame, and a vertically movable element including a mold-board; the combination of two tension springs acting between said frame and said movable element and exerting on said movable element a force greater than the weight thereof when the cutting edge of 75 said mold-board is at or below the level of the ground on which said wheels rest, and means for equalizing the tension of said two springs.

7. In combination with a road grader having a frame and a blade-carrying element vertically adjustable relative to said frame, a bar pivoted to one of said parts, 85 springs attached to the ends of said bar and to spaced points on the other of said parts.

8. In combination with a road grader having a frame and a blade-carrying element vertically adjustable relative to said frame, a bar pivoted to one of said parts, 90 springs attached to the ends of said bar and to the other of said parts.

In witness whereof, I have hereunto set 95 my hand at Indianapolis, Indiana, this 18th day of July, A. D. one thousand nine hundred and twenty-four.

WILLIAM A. COST.
